UNITED STATES PATENT OFFICE.

MADS M. LARSEN, OF COLTON, CALIFORNIA.

WINDOW ADJUSTER AND LOCK.

Application filed September 25, 1923. Serial No. 664,703.

To all whom it may concern:

Be it known that I, MADS M. LARSEN, a citizen of the United States, residing at Colton, in the county of San Bernardino and State of California, have invented new and useful Improvements in Window Adjusters and Locks, of which the following is a specification.

This invention relates to improvements in window adjusters.

An object is to provide an improved means for opening and closing a window. Another object is to provide a means which will hold a window in any desired position.

A further object is to provide a window adjuster which will lock a window in closed position, the locking parts being remotely situated from the sash.

The foregoing and other objects will be made manifest in the following specification of an embodiment of this invention illustrated by the accompanying drawings, in which:

Figure 1 is a horizontal section through a window frame in which the window adjuster is mounted.

Fig. 2 is an elevation of a window frame, parts being broken away and the sash being shown in open position.

Fig. 3 is a partial outside elevation of a window frame showing the application of the window adjuster.

Fig. 4 shows parts used in mounting the window sash to which the window adjuster is attached.

Referring to the drawings, in which similar reference characters designate similar parts, a window sash 10 has mounted preferably in one of its lower corners a socket 11 as by screws 12. Extending through the window sill 13 and into the socket 11 is a shank 14 shown as having a squared end 15 and suitably housed within a casing C hereinafter more fully described. Adjacent the lower end of the shank 14 and securely mounted thereon as by a key 16 is a pinion 17 engaging the gear 18 having a spindle 19 mounted within the aforementioned casing. A rack 20 which is slidable within the casing C engages the gear 18. The rack 20 is provided with an arm 21 extending through a slot 22 in the window frame 23, the arm 21 being threaded to receive a handle 24

which may be screwed down, as shown by dotted lines in Figure 1, upon a slotted plate 25 mounted upon the inside face 26 of the window frame.

It will be seen that when the handle 24 is freed from contact with the plate 25, the arm 21 and the rack 20 may be moved from side to side, producing rotation of the gear 18 and the pinion 17 together with the shank 14, which causes swinging movement of the window sash 10 upon a vertical axis, in this case. When the sash is in the desired position it may be frictionally locked in place by screwing down the handle 24 tightly against the plate 25.

The casing C enclosing the operating mechanism preferably consists of three pieces, including a member 27 having a slot 28 through which extends the arm 21 and also a groove 28a in which slides the rack 20. The pieces 29 and 30 have flanges 29a and 30a respectively for fastening to the member 27. These pieces are joined as at 31, and have recesses to receive the ends of the spindle 19 and are complementary with the exception that the piece 29 has a tubular portion 32 which houses the shank 14. It is seen that the casing encloses the entire operating mechanism, keeping it free from dirt and foreign matter.

When fastening the sash 10 to the window frame it is necessary that the upper point of attachment be directly above the shank 14 when the sash is to be swung about a vertical axis as shown. To this end the plate 33, having perforations 34 for mounting upon the top edge of the sash 10, is provided, having a pin 35 which is placed directly above the shank 14 and received by a bushing 36 which is recessed in the window frame and attached thereto by nails or screws passing through apertures 37 in the plate 38.

The threaded shank and the handle piece 24 provide for the ready adaptation of the device to window frame structures of different dimensions.

It is seen that a combination window adjusting device is provided which will hold the sash at any desired opening and which will lock the window when closed, the locking parts being inaccessible from the outside.

Further embodiments, modifications and variations may be resorted to within the principle of the invention.

What is claimed is:

5. 1. A window adjuster and lock comprising means adapted to be mounted within a window casing and having a member forming a pivot for the sash to be adjusted and operative to swing the sash, a handle disposed for access at the window casing, and means connecting the handle and said member whereby the latter is adapted to be rotated to swing the sash, said handle forming a friction locking device for securing the sash in its several positions.
10. 2. A window adjuster and lock comprising means adapted to be mounted within a window casing and having a member forming a pivot for the sash to be adjusted and operative to swing the sash, a handle disposed for access at the window casing, and means connecting the handle and said member whereby the latter is adapted to be rotated to swing the sash, said handle being adapted
15. 25. for reciprocating movement parallel to the face of the window casing and adapted to form a friction locking device for securing the sash in its several positions.
3. A concealable window adjuster and locking device including a rotative member connectible to a sash to be swung from one position to another on the axis of said member, a mounting part in which said member is journaled, gear means carried by said mounting part, a rack engaging said gear means, and a handle adapted to be disposed in an accessible position and whereby the rack and said gear means are operated to swing the sash, said handle including a threaded shank and a handle piece adjustably mounted on the shank.
30. 4. A concealable window adjuster and locking device including a rotative member connectible to a sash to be swung from one position to another on the axis of said member, a mounting part in which said member is journaled, gear means carried by said mounting part, a rack engaging said gear means, and a handle adapted to be disposed in an accessible position and whereby
35. 40. 45. 50. the rack and said gear means are operated

to swing the sash, said handle including a threaded shank and a handle piece adjustably mounted on the shank and whereby the adjuster parts may be locked in various positions.

5. A window adjuster and lock, comprising a mounting member adapted to be enclosed within the window casing, a pivot forming member for a sash, journaled within said mounting member whereby the sash may be turned on the axis of said pivot, a pinion carried by said pivot forming member, a gear engaging said pinion, a rack adapted to engage said gear and produce movement of said sash, and means for frictionally locking said rack in any position.

6. A window adjuster and lock comprising a pivot forming member, upon which a sash is adapted to be pivoted, means whereby said sash may be rotated by said pivot forming member, a pinion upon said pivot forming member, a gear meshing with said pinion, and means for rotating said gear so as to rotate said pinion and pivot forming member and thereby swing said sash.

7. A window adjuster and lock comprising a pivot forming member, upon which a sash is adapted to be pivoted, means whereby said sash may be rotated by said pivot forming member, a pinion upon said pivot forming member, a gear meshing with said pinion, and a rack meshing with said gear adapted to rotate it upon sliding movement whereby said pinion and pivot forming member may be rotated so as to swing the sash.

8. A window adjuster and lock comprising a pivot forming member, upon which a sash is adapted to be pivoted, means whereby said sash may be rotated by said pivot forming member, a pinion upon said pivot forming member, a gear meshing with said pinion, a rack meshing with said gear adapted to rotate it upon sliding movement whereby said pinion and pivot forming member may be rotated so as to swing the sash, and means for locking said rack in any desired position.

In testimony whereof I have signed my name to this specification.

MADS M. LARSEN.
